(57) **CLAIM**

The ornamental design for a fragrance compact, as shown and described.

DESCRIPTION

FIG. 1 is a top perspective view of the design;

FIG. 2 is a rear view of the design;

FIG. 3 is a front view of the design;

FIG. 4 is a left side view of the design;

FIG. 5 is a right side view of the design;

FIG. 6 is a top down view of the design;

FIG. 7 is a bottom up view of the design; and

FIG. 8 is a top perspective view of the design in an open configuration.

FIG. 9 is a left side view of the design in an open configuration.

FIG. 10 is a right side view of the design in an open configuration.

FIG. 11 is a rear view of the design in an open configuration.

FIG. 12 is a front view of the design in an open configuration.

FIG. 13 is a top down view of the design in an open configuration; and,

FIG. 14 is a bottom up view of the design in an open configuration.

The broken lines shown in the drawings are included for the purpose of illustrating portions of the fragrance compact that form no part of the claimed design.

1 Claim, 14 Drawing Sheets
